UNITED STATES PATENT OFFICE.

ARTHUR A. SHAFFER, OF ERIE, PENNSYLVANIA, ASSIGNOR TO RICKERT-SHAFFER COMPANY, OF ERIE, PENNSYLVANIA, A CORPORATION OF PENNSYLVANIA.

COLLAPSIBLE TAP.

1,345,710.

Specification of Letters Patent.

Patented July 6, 1920.

Application filed June 27, 1919. Serial No. 307,131.

To all whom it may concern:

Be it known that I, ARTHUR A. SHAFFER, a citizen of the United States, residing at Erie, in the county of Erie and State of Pennsylvania, have invented certain new and useful Improvements in Collapsible Taps; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to collapsible taps and has for its object the construction and arrangement of mechanism which will operate to expand the thread-cutting blades or chasers and firmly hold them in such position during the thread-cutting operation, and which, when the chasers have reached the end of their cut, will cause the chasers to instantly collapse from the work and permit the tap to be withdrawn without the necessity of reversing or backing out of the threads. In carrying out my invention I provide cam mechanism which is adapted to force the chasers outwardly to the required diameter and inwardly away from the work; the movement in either direction being positive. I also provide means whereby the outward movement of the chasers may be limited as may be desired.

These and other features of my invention and the mechanism preferably employed to embody them, are hereinafter fully explained and pointed out, and are illustrated in the accompanying drawings, in which:

Figure 1, is a central longitudinal section of my improved tap with parts in elevation.

Fig. 2, is a transverse section thereof on the line 2—2 in Fig. 1.

Fig. 3, is a longitudinal central section of a fragment thereof.

Fig. 4, is a central longitudinal section of the shell or body of my tap.

Fig. 5, is a view in elevation of the lower end thereof.

Fig. 6, is a transverse section on the line 6—6 in Fig. 1.

Fig. 7, is a transverse section on the line 7—8 in Fig. 1, looking downward.

Fig. 8, is a transverse section on the line 7—8 in Fig. 1, looking upward.

Fig. 9, is a side elevation of a fragment thereof.

Fig. 10, is a section of a portion thereof on the line 10 in Fig. 1.

In these drawings, A (see Figs. 4 and 5) indicates the body member of the tap, which is provided with radial slots A' as shown in Fig. 4. This body member A is hollowed out from the upper end, the inner end of said cavity terminating in an annular slot a'; which cuts down into the radial slots A', and leaves a concentric disk A² supported by the segments a² (see Fig. 5) between the radial slots A'. This disk A² is provided with a central opening A³. The wall of the body member A is provided with a slot a³ (see Fig. 9) for an operating lever, herein-after described.

Within the radial slots A' I place slidable blocks B (see Figs. 1 and 10) which are provided in their upper faces with transverse slots b (see Figs. 1 and 2) to receive a cam-ring C on the lower edge of a ring C' which is placed within the body A.

The slidable blocks B are secured in place in the radial slots A' by means of side-plates D—D (see Fig. 10) which side-plates are provided with ribs which enter the slots a in the side walls of the radial slots A', and are secured in position therein by means of screws d—d (as shown in Figs. 5 and 10).

Inserted upwardly through the central opening A³ (see Figs. 4 and 5) is a central shaft (see Fig. 1) having on the lower end thereof a series of cam surfaces E above which there is an annular shoulder E' which fits the opening A³, and above the shoulder E' an annular shoulder E² which fits the opening in the ring C', and above the shoulder E² the shaft E³ extends upwardly within the body A.

In the radial slots A³ I place chasers F (see Figs. 1 and 10) which are secured to the slidable blocks B by means of screws f so that said chasers and blocks will slide in unison, the inner edges of said chasers contacting with the cam surfaces E on the central shaft member, as shown in Fig. 1.

To secure the central shaft member in place within the body A I secure a disk G on the lower end of the body A by means of screws g which enter the tapped openings g' (see Fig. 5) in the lower end thereof. Preferably the disk G is provided with a central

opening in which a pivot post e on the lower end of the central shaft member is journaled as shown in Fig. 1. Preferably the blocks B, side-plates D and disk G are made of extra hard metal so they will not readily become worn or marred in use.

The ring C' is non-rotatably fixed to the annular shoulder E² of the central shaft member by means of a key e' (see Figs. 10 1 and 7) thereby causing said ring C' and central shaft member to rotate in unison, so that the cam E will force the chasers outward at one movement of the central shaft member and while so doing the cams on 15 the ring C (see Fig. 2) move away from the blocks B permitting the outward movement of the chasers F and blocks B, and on the reverse movement of the central shaft member the cams E move away from the chasers 20 and the cam-surfaces on the cam-ring C engage the blocks B and move said blocks and chasers secured thereto inward.

In the periphery of the ring C' I provide a circumferential slot H in which I place 25 a spring H' (see Fig. 6) one end of which engages a post A⁴ secured in the wall of the body A; and the other end thereof engages a post c² secured in the ring C'; said spring H' being thereby adapted to rotate 30 said ring in one direction.

Mounted upon the portion E² of the central shaft member is an operating ring J in which a hand lever J' is secured which projects outwardly through the slot a³ in the 35 wall of the body member A.

In the upper surfaces of the ring C' I provide a diagonal slot K, which I preferably make slightly curved as shown in Fig. 7; and in the lower face of the ring J I 40 provide a radial slot J² in which I place a slide J³ which has a projection J⁴ which enters the diagonal slot K in the ring C'. To operate the slide J³ I provide an adjusting screw J⁵ the ends of which respectively 45 engage the central shaft member E² and the inner wall of the body member A (see Fig. 1) said screw passing through said slide J³.

To give access to said screw J⁵ when the 50 mechanism is in the position shown in Fig. 1, I provide an opening j in the wall of the body member A. By turning said screw so as to move the slide J³ radially in the ring J the projection J⁴, traveling in the 55 diagonal slot K in the ring C' will cause said ring C' to rotate with relation to the ring J, thereby adjusting the throw of the cams E on the lower end of the central shaft member.

Slidably placed in the upper end of the 60 body member A is a shank-hub L, (see Fig. 1) which is provided with an annular shoulder L' of reduced diameter. Between the periphery of the hub L and the inner surface 65 of the body A I bore a plurality of holes,

preferably three equally spaced, half of each hole being in said hub and half in the wall of the body member, in which I place driving keys, or rods M (see Fig. 1) which compel joint rotary movement of the body A 70 and hub L. To maintain the hub L normally in contact with the ring J as shown in Fig. 1, I provide springs N, preferably two equally spaced, and located in holes, as provided for the keys M, one-half in the 75 hub and half in the body A; and to secure the keys M and springs N in place, and also to prevent the hub L from being withdrawn from the body A, I secure a ring O on the upper end of the body member A by means 80 of screws O'.

P indicates a shank screwed into the hub L. To lock the ring J in position shown in Fig. 1, which is the thread-cutting position of the tap, and in which the spring H' is 85 compressed, I provide a bolt R which is placed in a recess R' in the hub L and secured therein by means of a threaded bushing R², and is provided with a spring R³ to maintain it in locked position. The bolt 90 R enters a recess in the ring J and locks it in the position shown in Fig. 1.

In operation the hand lever is used to turn the ring J into the position shown, which through the adjusting slide J³ turns 95 the ring C' and central shaft member E—E² in unison therewith and compresses the spring H' until the locking bolt R enters the recess in the ring J, which locks the mechanism and maintains the chasers in 100 expanded position as shown. When the chasers F have reached the limit of their cut, the tap is forcibly moved backward from the work which causes a longitudinal movement of the shank-hub L away from 105 the ring J, and draws the locking-pin R out of the recess in the ring J, which releases the ring J so that it and the ring C' can be operated backward by the spring H', to collapse the chasers and allow the tap to be 110 withdrawn from the work without the necessity of unscrewing out of the work.

Having thus fully shown and described my invention so that the same can be utilized by others, what I claim as new and desire 115 to secure by Letters-Patent is:—

1. In a collapsible tap a body member having radial slots, chasers slidably mounted in said slots, a central shaft member in said body, cam surfaces carried thereby 120 adapted to force said chasers outwardly at one movement, and the cam ring mounted thereon and rotatable with said central shaft to force said chasers inwardly at the reverse movement thereof, substantially as 125 described.

2. In a collapsible tap, a body member having radial slots, chasers slidably mounted in said slots, a central shaft member, cam surfaces thereon adapted to move said 130

- chasers outwardly when turned in one direction, a ring non-rotatably secured on said shaft member, spring mechanism to rotate the same in the opposite direction, cam surfaces on said ring to move said chasers inwardly during the reverse movement of said shaft member, an operating ring on said shaft member, means to adjustably connect the same with the first mentioned 5 ring, a shank-hub slidably and non-rotatably mounted in said body member, a spring pressed locking bolt carried thereby and adapted to enter a recess in said operating ring when it has been rotated to its limit 10 in one direction, substantially as set forth.
3. In a collapsible tap, a body member having radial slots, chasers mounted in said slots, rotary cam mechanism adapted to move said chasers outward and inward, a 15 diagonal slot in said cam mechanism, an operating ring, a radial slot therein, a slide in said radial slot and projecting into said diagonal slot in said cam mechanism, an adjusting screw in said slide, a spring to rotate said cam mechanism to closing position, and a hand lever to rotate said operating 20 ring to expanded position, substantially as set forth.
4. In a collapsible tap, a body member having radial slots, slidable blocks in said slots, chasers in said slots secured to said blocks, a central shaft member, cam surfaces thereon adapted to engage said chasers to move them outwardly, a spring actu- 25
- ated ring non-rotatably secured on said shaft-member, cam surfaces thereon adapted to engage said slidable blocks to move them inwardly when said ring is actuated by its spring, an operating ring on said shaft-member, a lever to operate the same in one 30 direction, adjustable means to connect said spring-pressed ring and said operating ring, and means to lock said operating ring, substantially as set forth. 35
5. In a collapsible tap, a body member having radial slots in one end thereof, and a cylindrical chamber therein communicating with said slots, and an integral ring A^2 bridging the inner ends of said slots, substantially as set forth. 40
6. In a collapsible tap, a body-member having radial slots in one end thereof, chasers mounted therein, rotatable cam mechanism centrally mounted in said body member adapted to move said chasers outwardly 45 and rotatable cam mechanism to move said chasers inwardly a hand lever to rotate said cam mechanism outwardly, and spring mechanism to move the same in the opposite direction, a shank non-rotatably and slidably mounted in said body-member, means to yieldingly maintain the same in its innermost position, and a spring-pressed locking bolt carried thereby to maintain said cam mechanism in position to expand said chasers, substantially as described. 50
